UNITED STATES PATENT OFFICE.

WILTON S. BRAUD, OF BATON ROUGE, LOUISIANA.

ELECTRIC-LAMP-BULB MANIPULATOR.

Application filed April 18, 1924. Serial No. 707,493.

To all whom it may concern:

Be it known that I, WILTON S. BRAUD, a citizen of the United States, residing at Baton Rouge, in the parish of East Baton Rouge and State of Louisiana, have invented new and useful Improvements in Electric-Lamp-Bulb Manipulators, of which the following is a specification.

The object of my said invention is the provision of a device through the medium of which electric lamp bulbs can be positioned in sockets and removed therefrom without the use of a ladder which is ordinarily necessary when the sockets are located a considerable distance over head.

To the attainment of the foregoing, the invention consists in the improvement as hereinafter described and definitely claimed.

In the accompanying drawings, forming part of this specification:—

Figure 1 is a side elevation of the manipulator constituting the preferred embodiment of my invention.

Figure 2 is an edge elevation taken at right angles to Figure 1.

Figure 3 is a plan view of the upper end of the device.

Figure 4 is a cross-section taken in the plane indicated by the line 4—4 of Figure 1.

Similar numerals of reference designate corresponding parts in all of the views of the drawings.

Among other elements my novel manipulator comprises a handle 1 of appropriate length which may be and preferably is formed of wood.

Fixed to opposite sides of the handle 1 are standards 2, preferably of metal, which are brought into close proximity above the handle 1 as designated by 3 for the purpose of pivoting therebetween a lever 4, the pivot point of said lever being designated by 5. In this connection it will be noticed that the standard portions 3 are merged into curvilinear fingers 5' which are relatively arranged as shown and are covered with sleeves 6 of rubber or other appropriate padding material. The lever 4 includes three arms 7, 8 and 9. The arm 7 is curvilinear and is arranged opposite the space between the fingers 5 and is padded by a sleeve 10 of rubber or other appropriate material. The arm 8 of the lever 4 is connected by a retractile spring 11 with an intermediate point in the length of the handle 1. Connected to

the remaining arm 8 of the lever 4 and preferably, though not necessarily, connected at 12 to the lower portion of the handle 1 is a cable 13 through the medium of which an operator while holding the handle 1 in one hand is enabled with his other hand to conveniently move the padded arm 7 relative to the curvilinear padded fingers.

In the practical use of the manipulator, it will be manifest that an operator is enabled by moving the padded arm or finger 7 away from the fingers 5 to position the arm 7 and fingers 5 about an incandescent electric lamp bulb. Then when the arm 7 is permitted to move toward the fingers 5 the bulb will be securely grasped between the fingers 5 and arm 7 whereupon the bulb may be expeditiously and easily unscrewed and removed and this notwithstanding the fact that the bulb may be adjacent to a high ceiling.

When it is desired to utilize the device to put a bulb in an overhead socket or a socket otherwise out of reach, the bulb is placed by hand between the arm 7 and the fingers 5 whereupon the bulb is elevated through the medium of the handle 1 and is screwed through the medium of the handle 1 into the socket designed to receive it.

It will be manifest from the foregoing, that my novel device is efficient and convenient in operation and at the same time is simple and inexpensive in construction.

Having described my invention, what I claim and desire to secure by Letters-Patent, is:—

An electric lamp bulb manipulator comprising a handle, spaced standards fixed to and extending from said handle and terminating in curvilinear spaced fingers, a lever fulcrumed between the standards and formed in one piece and having an upstanding and curvilinear arm opposite the space between the said fingers and an outwardly extending arm at the same side of the fulcrum point as said curvilinear arm and a third arm extending at the opposite side of the fulcrum point, with reference to the two first-named arms, a retractile spring interposed between and directly connected to the handle and the third-named arm, and a cable connected to the second-named arm and pendent alongside the handle.

In testimony whereof I affix my signature.

WILTON S. BRAUD.
